Term of patent 7 years

Int. Cl. D23—03

U.S. Cl. D23—82

The sole figure is a perspective view of a hobby kiln showing my new design.

The hobby kiln of my design is symmetrical about a vertical axis so no other view is shown. The hobby kiln is designed to stand on its base so no bottom view is shown as it is conventionally plain and unornamented.

I claim:

The ornamental design for a hobby kiln, substantially as shown and described.
